HEAT PUMP CYCLE AND METHOD OF
OPERATING SAMEGilbert Wilkes, Jacksonwald, Pa., assignor to
Wilkes Avery Corporation, New York, N. Y., a
corporation of New York

Application July 28, 1933, Serial No. 682,721

8 Claims. (Cl. 62—115)

This invention relates to heat pump cycles, and more particularly to a method of operating such cycles and apparatus for use therein.

In operation, the ordinary heat pump cycle is fairly efficient so that the losses occurring in the cycle, particularly where the heat range temperature variation between evaporator and condenser elements is not great, are either unnoticed or overlooked. Attempted application of such cycles to situations where the temperature variations are considerable both increases the inefficiency of the cycle and renders this inefficiency highly noticeable. It is, therefore, obvious that where a heat pump cycle is employed in any situation where both ends of the cycle are to be employed, as for example, in modern dairy systems where the developed heat is used in pasteurization and the low temperatures in cooling the milk and formation of ice-cream and ices, the cost of operation becomes prohibitive. The decrease in efficiency is particularly noticeable where the high temperature requirements of the cycle demand use of the refrigerant at or near its critical point. This decrease in efficiency affects the hot end of the cycle by the increase in motive power required to compress the refrigerant to sufficient pressure for liquefaction at the higher temperatures, and affects the cold end of the cycle by passing to the evaporator a liquid near the critical point and containing therefore almost as much heat as the vapor is capable of absorbing for a useful cooling effect.

An important object of this invention is the production of a method of operation and apparatus for use in such method of operation which will permit recuperation of at least a portion of the work available in the saturated liquid withdrawn from the condenser in circulation of the refrigerant in the system.

Another general object of this invention is to increase the effectiveness of the evaporator on these high temperature differential cycles by providing a means of extracting by conversion into mechanical work, a certain portion of the sensible liquid heat.

A more specific object of the invention is the combination with a reciprocating type compressor of a recuperative motor having driving connection with this compressor and having means whereby a regulated supply of liquid withdrawn from the condenser may be evaporated therein and in evaporation release work to assist in driving the compressor.

A still further object of the invention is the

adaptation of this recuperative principle to the rotary or gear pump type of compressor as employed in heat pump cycles.

A still further object of the invention is the adaptation of this principle to ejector cycle heat pumps.

These and other objects I attain by the construction shown in the accompanying drawings wherein, for the purpose of illustration, I have shown a preferred embodiment of my invention and wherein:

Fig. 1 is a semi-diagrammatic view illustrating a heat pump cycle including a reciprocating pump and incorporating my invention;

Fig. 2 is an enlarged sectional view through the recuperative motor employed in Fig. 1;

Fig. 3 is a semi-diagrammatic view showing my invention as applied to a heat pump cycle including a rotary compressor;

Fig. 4 is a detail sectional view showing a method of mounting the compressor and recuperative motor; and

Fig. 5 is a diagrammatic view illustrating my invention as applied to an ejector cycle heat pump.

Referring now to the drawings, and more particularly to Figs. 1 and 2, the numerals 10 and 11 indicate respectively the condenser and evaporator of a heat pump cycle, and the numeral 12 a compressor for circulating a refrigerant through the condenser and evaporator and connected in series with the condenser and evaporator.

In accordance with my invention, I provide a recuperative motor generally designated at 13 and including a cylinder 14, a piston 15 reciprocating in this cylinder and having driving connection with the shaft 16 of the reciprocating compressor 12. In the present instance, the shaft 16 is shown as extended and provided with a crank 17 mounting the connecting rod 18 of piston 15. The shaft 16 is equipped with a cam 19 controlling an exhaust valve 20 for cylinder 14. The exhaust chamber 21 of recuperative motor 13 is placed in communication with the intake of evaporator 11 while the intake of this motor is in communication with the outlet of condenser 10 through a liquid supply chamber designated at 22.

Liquid supply chamber 22 contains a suitable means for controlling the amount of liquid delivered to the motor 13. This control means is at present indicated as comprising a cam-operated tappet 23, the cam 24 of which is mounted upon shaft 16 and which tappet actuates through the lever arm 25 a valve 26 controlling admission to the cylinder 14 of motor 13. Since the amount

of liquid delivered will be variable, a means for controlling to compensate for this variation is shown in float ball 27 operating through suitable leverage 28 upon a wedge element 29 inserted 5 between sections of tappet rod 23.

It will be obvious that in operation the drive motor 30 of the reciprocating compressor will cause reciprocation of piston 15 in its cylinder. As the piston starts to move downwardly in the 10 cylinder, vapor is expanded from the admitted charge and in expanding releases available work which is imposed against the piston, forcing the same downwardly. The pressure applied to the piston as a result of expansion of the vapor will 15 continue with progressive expansion until the piston has reached the approximate lower limit of its stroke, after which valve 20 will open permitting the piston to discharge the expanded gases and residual liquid to the evaporator 11 as the 20 piston rises. The forces exerted against piston 15 thus act to assist the motor 30 in its operation and to enable the use of a much smaller motor than could be employed ordinarily.

In Fig. 3, the application is to the rotary type 25 compressor cycle and the numeral 31 generally designates a rotary compressor withdrawing refrigerant from an evaporator 32 and discharging the same to a condenser 33. Between the outlet of the condenser 33 and the inlet of evaporator 32 30 the recuperative motor 34 is disposed, the motor and compressor, as more clearly shown in Fig. 4, having a common drive and being preferably mounted in a common case 35 having an internal partition 36 separating the units. In this type 35 of construction, advantage is taken not only of the forces generated by expansion, but likewise of the pressure of liquids delivered from the condenser 33 which are but slightly below the delivery pressures of compressor 31. Liquid delivered 40 from the condenser to recuperative motor 34 is passed through a control chamber 37 containing means for separating the liquid from gases, at present shown as a float valve 38. This float valve co-operates with a suitable stop 39 in such 45 manner that the valve element 40 thereof never completely closes and a slight flow of liquid will be maintained even though the supply from condenser 33 should fail. It will be obvious that the expansion of vapor from this liquid in recuperative motor 34 and the pressure of the delivered 50 liquid will act to assist in operation of compressor 31, thus reducing the size of the necessary operating motor 41.

I have further incorporated an arrangement 55 whereby the use of a viscous sealing medium such as glycerin may be resorted to in a system of this character. Separation of this medium from the gas discharged from compressor 31 is a comparatively simple matter, and, as at present shown, 60 is accomplished by a trap 42 having a liquid outlet 43 controlled by a float ball 44. This outlet discharges at the inlet of the recuperative motor 34 and the pressure of this sealing liquid will, of course, assist in the operation of the motor. From 65 the motor, the sealing liquid is carried to the evaporator 32 in which the liquid level is maintained at or about the indicated point. The sealing liquid employed is lighter than the refrigerant and, accordingly, rises to the upper ends of 70 the condenser coils where it is carried off by the boiling liquid to a separator chamber 45. From the separator chamber the refrigerant gases are conducted to compressor 31 through conduit 46 while the sealing liquid is conducted to the compressor through a conduit 47. Since the stop 48

of trap 45 maintains the valve 49 of the trap slightly open at all times, conduit 47 is provided with a valve 50 which is closed except during operation of the compressor. Valve 50 may be controlled in any suitable manner being generally illustrated in the present instance as electrically controlled by a thermostat 51 controlling motor 41.

In Fig. 5 an ejector type heat pump cycle is illustrated. In this figure 52 designates a boiler containing the refrigerant liquid and heated by a thermostatically controlled burner 53. Vaporized refrigerant passes from the boiler through a conduit 54 to the impeller jet 55 of an ejector compressor 56. The outlet of compressor 56 communicates with a condenser 57 operating as a heating coil while the low pressure inlet of the ejector communicates with the outlet of an evaporator 58 operating as a chilling coil. A connection between the outlet end of the condenser coil and the inlet end of the evaporator coil, indicated at 59, includes a trap 60 which, in addition to the outlet communicating with the evaporator has a further outlet 61 permanently in communication with the outlet of condenser coil 57 through the trap chamber. While the outlet 61 might communicate directly with the outlet of coil 57, the chamber of the trap is preferred as a means of communication since it provides a ready basin for fluid supply.

The numeral 62 designates a boiler feed injector, the impelling nozzle 63 of which is in communication with the outlet of condenser coil 57 through a conduit 64. The low temperature inlet of this injector is connected to the trap outlet 61. Conduit 64 and trap outlet 61 have arranged 105 therein valves 65 and 66 which valves, as indicated, are controlled by the level in boiler 52. The connection 59 between the outlet of trap 60 and evaporator coil 58 includes a cooler 67 at present illustrated as a coil surrounding outlet 61 where- 110 by the liquid passing through coil 61 is materially reduced in temperature. The outlet of the boiler feed injector 62 is connected through a conduit 68 with boiler 52, conduit 68 containing a check valve 69 opening toward the boiler. A 115 branch 70 of conduit 68 communicates with the inlet of a trap 71 which is located above the level of liquid in evaporator coil 58 and has its outlet in communication with the coil at this level. The trap is constructed to permit the passage of vapor 120 while preventing the passage of liquids and from the lower end of the trap a leak 72 so that liquid collecting in the trap may evaporate to the circulation system after an injecting operation, as 125 hereinafter described.

The operation of a boiler feed injector of this type depends upon the availability of a high temperature vapor as motive medium expanded off the saturated liquid, and on a supply of sub-saturated liquid to condense the motive vapor. In 130 the type of injector of Fig. 5, both the motive and condensing medium are of the same pressure. After priming, the pressure in the mixing chamber of the injector will be considerably lower than that of the condensing liquid so that the path of 135 flow of this condensing liquid can converge as well as that of the motive mixture, to transfer the pressure head available into velocity with the maximum efficiency.

In operation of this form of apparatus, vapor 145 passing from the boiler acts through ejector 56 to deliver vapor to condenser coil 57. Liquid from this coil passes through trap 60 to evaporator coil 58 and the vapor boiling off from this evaporator coil is recompressed and introduced to the con- 150

denser 57. When the refrigerant withdrawn from boiler 52 in the form of vapor reduces the level in this boiler to a predetermined point valves 65 and 66 are opened. With opening of valves 5 65 and 66, liquid passes directly from the condenser coil 57 to the impelling nozzle 63 of injector 62; at the same time cooled liquid refrigerant is delivered through outlet 61 from trap 60 to the low temperature inlet of the injector. This 10 liquid will be delivered through line 70 to trap 71 until the outlet of this trap is sealed, after which the injector will lift check 69 and deliver the liquid to the boiler 52. Trap 71 merely acts as a receptacle for liquid to insure priming of the injector.

15 It will be obvious from the foregoing that I am enabled by following the outlined method to render available energy released through expansion in the form of vapor of a portion of the saturated liquid to assist in circulation of the refrigerant in the system.

20 Since this method is capable of considerable variation in adaptation to various types of refrigerant systems, I do not wish to be understood 25 as limiting myself thereto or to the apparatus for carrying out the method except as hereinafter claimed.

I claim:

30 1. In operation of an ejector type heat pump comprising means to heat a body of refrigerant liquid, means to condense the vapor thus produced to a saturated liquid, and means to evaporate part of said saturated liquid, the method comprising expanding a portion of the liquid condensed and utilizing the energy released by expansion of the liquid to return liquid from the condenser to the heating means.

35 2. In operation of an ejector type heat pump comprising means to heat a body of refrigerant liquid, means to condense the vapor thus produced to a saturated liquid, and means to evaporate part of said saturated liquid, the method comprising expanding vapor off a portion of the condensed liquid, cooling another portion of the condensed liquid to recondense the expanded vapors and utilizing the energy released by the expansion of the first-named portion of the liquid to deliver the cooled liquid to said heating means.

40 3. In operation of an ejector type heat pump comprising means to heat a body of refrigerant liquid, means to condense the vapor thus produced to a saturated liquid, and means to evaporate part of said saturated liquid, the method comprising expanding vapor off a portion of the liquid condensed and utilizing the energy released by expansion of the liquid to return liquid from

the condenser to the heating means, and utilizing the speed and pressure of vapor delivered to the condenser to recompress vapors from the evaporating means in the condenser.

4. In operation of an ejector type heat pump comprising means to heat a body of refrigerant liquid, means to condense the vapor thus produced to a saturated liquid, and means to evaporate said saturated liquid, the method comprising expanding vapor off a portion of the condensed liquid, sub-cooling a portion of the condensed liquid to secure recondensation of said vapor and utilizing the energy released by the expansion of the first-named portion of the liquid to deliver the cooled liquid to said heating means, and utilizing the speed and pressure of vapor delivered to the condenser to recompress vapors from the evaporating means in the condenser. 80

5. Heat pumping apparatus comprising a condenser, means to deliver a vaporized refrigerant under pressure to said condenser for condensation to a liquid therein, and means to expand at least a portion of the liquid into vapor constructed and arranged to utilize the energy released in expansion of vapor from the liquid to return the refrigerant to the first-named condenser. 85

6. Heat pumping apparatus comprising a condenser, means to deliver a vaporized refrigerant under pressure to said condenser for condensation to a liquid therein, an evaporator to which the condenser discharges, and means to expand at least a portion of the liquid constructed and arranged to utilize the energy released in expansion of vapor from the liquid to return the refrigerant to the first-named condenser through 100 said means. 105

7. In an ejector type heat pump, a boiler, a condenser and an evaporator, series connections between the condenser and evaporator, a vapor connection between the boiler and condenser and 115 an injector operated by expansion of vapor from saturated liquid withdrawn from the condenser for withdrawing liquid from the condenser and returning it to said boiler.

8. In an ejector type heat pump, a boiler, a condenser and an evaporator, series connections between the condenser and evaporator, a vapor connection between the boiler and condenser including an ejector withdrawing vapor from the evaporator and recompressing it in the condenser, 120 and an injector operated by expansion of vapor from saturated liquid withdrawn from the condenser for withdrawing liquid from the condenser and returning it to said boiler. 125
